George D. Webster ATTORNEY

UNITED STATES PATENT OFFICE.

MABEL AARON, OF STOCKTON, CALIFORNIA.

DISH-WASHING DEVICE

1,133,691.

Specification of Letters Patent. Patented Mar. 30, 1915.

Application filed September 5, 1914. Serial No. 860,434.

To all whom it may concern:

Be it known that I, MABEL AARON, a citizen of the United States, residing at Stockton, in the county of San Joaquin, 5 State of California, have invented certain new and useful Improvements in Dish-Washing Devices; and I do declare the following to be a clear, full, and exact description of the same, such as will enable 10 others skilled in the art to which it appertains to make and use the same, reference being had to the accompanying drawings, and to the characters of reference marked thereon, which form a part of this application.

This invention relates to an improvement in a dish washing device and is particularly adaptable where a source of water supply is at hand and it is desired to wash the 20 dishes without putting the hands into the water any more than is necessary. By using this device, very warm water may be used without burning the hands, thereby cleaning the dishes more quickly and by using one of 25 the modified forms, many various conditions may be met.

A further object of the invention is to produce a simple and inexpensive device and yet one which will be exceedingly effective for the purposes for which it is designed.

These objects, I accomplish by means of such structure and relative arrangement of the parts as will fully appear by a perusal 35 of the following specification and claim.

On the drawings, similar characters of reference indicate corresponding parts in the several views.

Figure 1 is a side view of the preferred form of the device. Fig. 2 is a cross section on a line X—X of Fig. 1. Fig. 3 is a top view of the soap container. Fig. 4 is a side elevation of a modified form as used for washing bottles and the like. Fig. 5 is a side elevation of a modified form as used in combination with a scraper. Fig. 6 is a view from the bottom of the scraper.

Referring now more particularly to the characters of reference on the drawings, the numeral 1 designates the handle of the device which is riveted into a cup 2 formed on the cap 3 having threads 4 corresponding to similar threads upon the top portion of the soap container 5. Within this annular soap container, I have provided, in the lower part thereof, cross pieces 6 which will keep

the soap from dropping into the lower portion of the device. Projecting from the side of the soap container, I have provided a short nipple 7 with a rubber hose 7^a connected thereto leading off to any suitable source of water supply. The water entering through the hose and nipple into the soap container will run over the soap placed upon the cross pieces 6 and down into the conically formed member 8 screw fastened to the soap container, as at 9, and out through the holes 10 onto a dish cloth 11 fastened to the member 8 by means of a cap 12 having threads 13 corresponding to similar threads upon the nipple 14 of the member 8. The threads in the cap 12 are made deep enough to allow the thickness of the dish cloth to lie between the cap and the nipple thereby providing a means of fastening the cloth to the device. To rinse the dishes the soap is removed from the container and clear water run therethrough.

Fig. 4 is a modified form of the device as used for washing bottles or jars and has a handle 1^a fastened to a cap 2^a screw mounted upon the soap container 3^a having a means of receiving a water supply, as at 4^a. To the lower portion of the soap container, I have fastened, by means of threads, a cover 5^a having an opening into the pipe 6^a provided with holes 7^a so that the water may be sprayed immediately adjacent the cloth 8^a fastened to the end of the pipe 6^a.

Fig. 5 is a modified form of the device 90 as used in combination with a scraper for cleaning pans and the like. I have provided a handle 1^b fastened to a cap 2^b screw mounted upon the soap container 3^b having a means of receiving a water supply, as at 4^b. Fastened to the soap container 3^b by means of threads, is a conically formed member 5^b having holes 6^b and screw fastened to the nipple 7^b of the said member 5^b I have provided a cap 8^b having downwardly projecting arms 9^b riveted, as at 10^b, to a scraper plate 11^b provided with points 12^b and 13^b. The point 12^b is made long and sharp as shown to provide a ready means of cleaning small corners or other inaccessible 100 places.

From the foregoing description it will readily be seen that I have produced such a device as substantially fulfills the objects of the invention as set forth herein.

While this specification sets forth in detail the present and preferred construction

of the device, still in practice, such deviations from such detail may be resorted to as do not form a departure from the spirit of the invention as defined by the appended 5 claim.

Having thus described my invention what I claim as new and useful and desire to secure by Letters Patent is:—

A device of the character described comprising a soap container having a handle, a 10 conical shaped member communicating with said soap container and provided with a

plurality of holes, a projecting threaded nipple on the lower end of said conical shaped member, and a member having an interiorly 15 threaded cap adapted to be screw mounted on said nipple, as described.

In testimony whereof I affix my signature in presence of two witnesses.

MABEL AARON.
